CIGAR OR THE LIKE AND METHOD OF MAKING THE SAME

Ernst Rolf Detert, Lubbecke, Westphalia, Germany, assignor to Firma Eduard Gerlach G. m. b. H., Lubbecke, Westphalia, Germany

No Drawing. Application September 28, 1955
Serial No. 537,303

9 Claims. (Cl. 131—140)

The present invention relates to an improved cigar or the like and to a method of making the same, and more particularly it relates to a cigar having an improved color and improved burning characteristics.

It is known to be desirable to improve the color of cigar wrappers by either darkening or lightening the original color thereof and also by reducing the visibility of blemishes in the wrapper, and it is also known to be desirable to improve the color of the ash formed by smoking the cigar. It is generally desired to obtain as light as possible an ash, preferably an ash of nearly white color.

It is therefore an object of the present invention to apply color and ash-improving materials to the wrapper of a cigar or the like so as to achieve the above mentioned improvements.

It is another object of the present invention to apply color and ash-improving materials to the cigar wrapper in such a way that these materials firmly adhere to the wrapper.

It is still another object of the present invention to improve the color of a cigar and the color of the ash formed upon smoking of the cigar by applying to the cigar wrapper suitable materials in such a way that these materials will not be wiped or rubbed off the cigar wrapper and also will not be dissolved by the saliva of the smoker.

It is yet another object of the present invention to so apply color and ash-improving materials to the wrapper of a cigar or the like that any small holes in the wrapper will be closed by the applied materials and consequently the draft of the cigar will be improved.

Other objects and advantages of the present invention will become apparent from a further reading of the description and the appended claims.

With the above objects in view, the present invention comprises in a method of improving the color and burning characteristics of cigars and the like, the steps of treating the wrapper of a cigar or the like with a colloidal solution including distributed therethrough at least one coloring material adapted to color the wrapper and at least one ash-forming substance which upon burning forms an ash of predetermined color, and drying the wrapper treated with the colloidal solution so as to cause adherence of the coloring material and the ash-forming substance to the wrapper, whereby the wrapper is given a desired color before the cigar or the like is smoked and whereby the ash of the cigar or the like upon smoking of the same is also given a desired color.

The present invention also consists in a cigar or the like as a new article of manufacture, the cigar or the like according to the present invention including a wrapper and having adhering and substantially evenly dis-

2

tributed on the outer face of the wrapper at least one coloring material adapted to color the wrapper and at least one ash-forming substance which upon burning forms an ash of predetermined color, and a thin substantially colorless film covering the wrapper and the coloring material and ash-forming substance adhering thereto, whereby the wrapper is given a desired color before the cigar or the like is smoked and the ash of the cigar or the like upon smoking of the same is also given a desired color.

According to the present invention the color and ash-improving material is formed of inorganic pigments such as titanium dioxide, magnesium carbonate, calcium carbonate, talcum, kaolin, or the like whereby the pigments are preferably colored with completely combustible organic natural or synthetic coloring materials, or with natural color pigments such as tobacco powder, and whereby the pigments are evenly distributed in a liquid colloidal system. The liquid colloidal system containing the pigments and the coloring material, and also containing a synthetic or natural swelling agent is then applied to the cigar wrapper. An easily vaporizable solvent may be used in connection with forming the liquid colloidal system, such as a mixture of water and one of the lower alcohols. It then suffices to wet the wrapper of the cigar or the like with this mixture to such an extent that the suspension penetrates into the pores of the wrapper. After drying-off of the solvent, the pigment and the coloring material will then firmly adhere to the wrapper.

The following list of coloring materials is given as illustrative only, the scope of the invention however not being limited to the specific coloring materials listed below:

LIST OF COLORING MATERIALS

(a) Natural coloring materials such as:

Chlorophyll
Yellow wood extract
Buckthorn berries extract
Logwood extract

Hematein

Litmus

Safflower

Luteolein

Humic acid

(b) Synthetic coloring materials:

Food colors such as:

Indanthrene blue RS (BASF)
Thiazine brown (Bayer)
Tartrazine XX pure (Bayer)
Black 5410 (Bayer)
Yellow 27 175 N (Bayer)

The various preparations which may be used in accordance with the present invention may be applied to the cigar wrapper in various known ways and by using various suitable devices. The preparation may for instance be applied by spraying the same onto the cigar or by rolling the cigar between layers of sponge rubber or other suitable foam materials which are imbibed with the preparation.

The inorganic pigments or ash-forming materials, such as titanium dioxide or the like which thus have been finely distributed on the cigar wrapper remain after the smoking of the cigar as a fine white layer on the cigar ash.

The immediately following examples as well as the examples further below are given as illustrative only, the

invention however not being limited to the specific details of any of the examples in this specification.

PREPARATIONS FOR LIGHTENING THE COLOR OF THE WRAPPER

Example 1

(Using natural coloring materials)

	Parts	
Magnesium carbonate	55,000	10
Titanium dioxide	50,000	
Buckthorn berries extract	12,000	
Sodium humate	27,000	
Hematein	0,200	
Water	526,800	15
Aluminum sulfate	22,000	
Potassium nitrate	60,000	
Sorbitol in 30% aqueous solution	30,000	
Solution of gum arabic	45,000	
Tobacco powder	50,000	20
Starch	50,000	
Tragacanth	2,000	
Methanol	70,000	
	1,000,000	25

Example 2

(Using natural and synthetic pure food coloring materials)

	Parts	
Magnesium carbonate	27,500	30
Titanium dioxide	90,000	
Talcum	16,000	
Buckthorn berries extract	16,500	
Sodium humate	16,000	
Thiazine brown	3,550	35
Indanthrene blue	3,500	
Water	469,950	
Aluminum sulfate	20,000	
Potassium nitrate	80,000	
Sorbitol in 30% aqueous solution	30,000	40
Gum arabic in 25% aqueous solution	45,000	
Tobacco powder	70,000	
Starch	30,000	
Methanol	80,000	
Tragacanth	2,000	45
	1,000,000	

Example 3

(Without tobacco powder, using natural, and synthetic food coloring materials)

	Parts	
Magnesium carbonate	55,000	
Titanium dioxide	40,000	
Talcum	10,000	
Buckthorn berries extract	12,000	55
Sodium humate	16,000	
Thiazine brown	3,000	
Indanthrene blue	3,800	
Water	531,200	60
Aluminum sulfate	22,000	
Potassium nitrate	60,000	
Sorbitol in 30% aqueous solution	30,000	
Gum arabic in 25% aqueous solution	45,000	
Starch	100,000	
Methanol	70,000	65
Tragacanth	2,000	
	1,000,000	

The preparations described in Examples 1 to 3 are prepared as follows:

The inorganic pigments and the coloring materials are stirred into the water and heated to about 80° C. under constant stirring. Thereby the coloring materials are dissolved. Thereafter aluminum sulfate is added in

small portions in order to fix the coloring materials on the pigments. Thereby carbon dioxide is formed. After the generation of carbon dioxide has ended, the following ingredients are added under constant stirring and in the sequence in which they are listed: potassium nitrate, sorbitol solution, gum arabic solution and tobacco powder (if any). Starch is added after the mixture is cooled to below 40° C. Thereafter a suspension of tragacanth in methanol is introduced into the mixture. After the mass has been completely cooled, the same is passed through a colloid mill and is then ready for use.

Example 4

15 PREPARATION FOR DARKENING THE COLOR OF THE WRAPPER

	Parts	
Carmine red (pure food)	1,200	
Sodium humate	70,000	
Water	200,000	
Magnesium nitrate in 20% aqueous solution	200,000	
Magnesium carbonate	20,000	
Invert sugar	25,000	
Potassium nitrate	15,000	
Tragacanth	1,500	
Methanol	100,000	
Water	367,300	
	1,000,000	

The preparation described in Example 4 is prepared as follows: The food color carmine red and the sodium humate are dissolved under heating in 200,000 parts of water, thereafter under stirring 200,000 parts of a 20% aqueous magnesium solution are added, immediately followed by the magnesium carbonate, invert sugar and potassium nitrate. Thereafter the balance of the water is added and finally under continued stirring a suspension of the tragacanth in methanol is introduced into the mixture.

The preparations described in Examples 1 through 4, upon being applied to the wrapper of a cigar or the like and subsequent drying of the cigar will firmly adhere to the wrapper.

In certain cases it is desired to further treat the cigar wrapper to which in a first treatment a preparation such as for instance described in one of the foregoing examples has been applied. The purpose of this additional treatment is to further improve the appearance of the cigar and to more closely simulate the natural color of a wrapper by making the same less dull and slightly less even colored. It is also sometimes desirable to prevent potential detachment of the preparation from the mouth end of the cigar that may be caused by the saliva of the smoker.

It is therefore within the scope of the present invention to apply a film-forming substance to a cigar or the like, after first treating the same with a color and ash-improving preparation such as described above. The film-forming substance after being applied to the wrapper in the form of a solution and after drying of the thus treated cigar, will form a film adhering to the wrapper and covering the previously applied color and ash-improving substances. The thus formed film will create a natural gloss on the wrapper and protect the coloring and ash-improving material from contact with the saliva of the smoker.

The following list of film-forming substances and solvents therefor is given as illustrative only, the present invention however not being limited to the specific substances listed. Additional film-forming substances may be chosen which are soluble in low boiling solvents and which upon drying-off of the solvent will form a thin colorless and transparent film capable of adhering to the wrapper on a cigar.

LIST OF FILM-FORMING SUBSTANCES

Cellulose acetate
Cellulose ethyl ether
Cellulose methyl ether
Polyvinyl acetate
Polyvinyl ethyl acetal
Cellulose glycolic acid and soluble salts thereof
Alginic acid and soluble alginates

SOLVENTS FOR THE FILM-FORMING SUBSTANCES

Methanol
Ethanol
Propanol
Isopropanol
Butanol
Butyl acetate
Ethyl glycol
Methyl glycol
Acetone
Methylethyl ketone
Carbon tetrachloride
Trichlorethylene
Perchlorethylene
Chloroform

Preparations for the above described film-forming treatment of wrappers for cigars or the like may for instance have the compositions described in the following Examples 5 to 7:

Example 5

	Parts
Acetyl cellulose	50,000
Butyl acetate	100,000
Ethyl acetate	100,000
Isopropanol	200,000
Methanol or ethanol	550,000
	1,000,000

Example 6

	Parts
Ethyl cellulose	25,000
Methanol	250,000
Isopropanol	475,000
Carbon tetrachloride	250,000
	1,000,000

Example 7

	Parts
Ethyl cellulose	25,000
Methanol	250,000
Isopropanol	725,000
	1,000,000

According to a preferred embodiment of the method of the present invention a water-soluble calcium magnesium or aluminum salt, for instance the formic acid salt of these metals, is included in the preparation used for improving the color and ash of the cigar. After drying-on of this preparation, the wrapper is then treated with a solution of a water-soluble salt of alginic acid such as sodium alginate. The water-soluble alginate then reacts with the calcium, magnesium or aluminum to form an insoluble alginate, first as a gel, and after drying of the treated cigar as a film firmly adhering to the wrapper. This after-treatment is preferably executed by wetting the pretreated wrapper of the cigar or the like with the solution of the soluble alginate, and drying of the cigar after the insoluble alginates have been formed, at a temperature of preferably about 40 to 50° C. Best results are achieved if the colloidal solution used for the first treatment of the wrapper contains not less than 2% preferably about 5% of soluble salts of calcium, magnesium or aluminum.

The preparation used for forming the insoluble alginate film may for instance be composed as follows:

Example 8

	Parts
5 Sodium alginate	20,000
Sodium metaphosphate	5,000
Water	875,000
Methanol	100,000
	1,000,000

It is an added advantage of the preparation described in Example 8 that the same is non-inflammable.

Similar satisfactory results are obtained when instead of alginates, salts of cellulose glycolic acid are used which are soluble in a mixture of water and lower alcohols. These salts too form insoluble films of calcium, magnesium and especially aluminum salts when applied in solution to a cigar wrapper previously treated with a preparation containing soluble magnesium calcium or aluminum salts.

A preparation containing a soluble salt of cellulose glycolic acid instead of a soluble alginate may for instance be composed as follows:

Example 9

	Parts
Sodium salt of cellulose glycolic acid	20,000
Water	500,000
Methanol	480,000
	1,000,000

According to another preferred embodiment of the present invention the color and ash-improving materials are further fixed to the wrapper by an after-treatment with a solution of the alkaline earth or aluminum salts of cellulose glycolic acid which by themselves are insoluble in water but have the property of swelling in an aqueous methanol, ethanol or isopropanol solution in the presence of small quantities of ammonium hydroxide. The wrappers of cigars which have first been treated for instance with a preparation as described in Examples 1 to 4, may, according to this preferred embodiment of the present invention, be after-treated with a gel such as for instance described in the following example:

Example 10

	Parts
Aluminum salt of cellulose glycolic acid	20,000
Aqueous ammonia solution containing 25% ammonium hydroxide	8,000
Water	472,000
Methanol	500,000
	1,000,000

Preparations such as described in Examples 5 to 7 may also be used for fixing to a wrapper color and ash-improving materials which originally were applied to the wrapper in dry powder form.

It is also within the scope of the present invention to include in any of the preparations, such as described in the examples, suitable odorous substances or extractives such as extract of licorice, cedar-wood oil, attar of roses or honey.

According to the embodiment of the present invention wherein the wrapper of a cigar which has first been treated with a material adapted to improve the characteristics of said cigar with respect to the color of the same and the color of the ash formed upon smoking of the cigar, and to which is then applied a film-forming substance adapted to form a film upon drying, it is achieved that solid powder particles such as pigments, which may have been applied to the wrapper either dry or in suspension, are then embedded in an insoluble film layer. In addition to thus fixing the color and ash-improving ma-

terials to the wrapper so that the same cannot be wiped off or dissolved, the film gives the cigar a desirable natural gloss. Film-forming preparations according to the present invention, as for instance described in Examples 5 to 10, are so composed as to in no way influence the taste of the cigar upon smoking, and so that the products formed during burning of the cigar are similar to those which are formed during the burning of an untreated wrapper.

It is of course important in accordance with the method of the present invention that the solvents used for dissolving the film-forming substance, such as lower alcohols, esters, ketones, ethers, halogenized compounds or other solvents (all of which are characterized by being easily vaporizable at relatively low temperature for instance 40 to 50° C.) are completely removed during the drying of the treated cigar. It is therefore advisable to use low boiling solvents of great purity and to execute the drying operation in a drying device through which considerable quantities of air are constantly flowing.

According to another preferred embodiment of the method of the present invention, the two treatments above described, that is the application of color and ash-improving materials and the subsequent forming of a film on the wrapper, are combined into one treatment step by for instance suspending the colored, dried and finely ground pigments of Examples 1 to 4 in a film-forming solution according to Examples 5 to 7. This combined preparation may then be applied to the cigar in one wetting step, and the cigar then dried as described further above.

A preparation suitable for this combined treatment may for instance be composed as described in the following example:

Example 11

	Parts
Ethyl cellulose	50,000
Pigment	25,000
Methanol	250,000
Isopropanol	675,000
	1,000,000

Preferably, for the treatment of 1,000 cigars of average size about 250 grams of preparations according to Examples 1 to 4 and about 150 grams of preparations according to Examples 5 through 10 are used. This amounts to about 5.7 milligrams of preparations according to Examples 1 to 4 and to about 3 milligrams of preparations according to Examples 5 through 10 and to about 4 mg. of preparations according to Example 11 per square centimeter of wrapper.

In addition to improving the color of the wrapper and of the ash formed upon smoking of the cigar, the treatment according to the present invention also improves the draft of the cigar by closing pores and small holes in the wrapper. The term "cigar" as used herein is meant to denote cigars, cigarillos and any other smoking product which is covered with a tobacco leaf wrapper.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

I claim:

1. In a method of improving the color and burning characteristics of cigars and the like, the steps of treating the wrapper of a cigar or the like with a liquid colloidal system distributed therethrough at least one completely combustible coloring material adapted to color said wrapper and at least one ash-forming substance which upon

burning forms a white ash; drying said wrapper treated with said colloidal system so as to cause adherence of said coloring material and said ash-forming substance to said wrapper, whereby said wrapper is given a desired color before the cigar or the like is smoked and whereby the ash of the cigar or the like upon smoking of the same is whitened; treating said wrapper with said coloring material and said ash-forming substance thereon with a solution of cellulose ethyl ether adapted to form a film upon drying; and drying said wrapper treated with said film-forming substance, thereby forming a film on said wrapper substantially covering said coloring material and said ash-forming substance.

2. In a method of improving the color and burning characteristics of cigars and the like, the steps of treating the wrapper of a cigar or the like with a liquid colloidal system distributed therethrough at least one coloring material adapted to color said wrapper and at least one white pigment; drying said wrapper treated with said colloidal system so as to cause adherence of said coloring material and said white pigment to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution of cellulose ethyl ether adapted to form a film upon drying; and drying said wrapper treated with said film-forming substance, thereby forming a film on said wrapper substantially covering said coloring material and said ash-forming substance.

3. In a method of improving the color and burning characteristics of cigars and the like, the steps of treating the wrapper of a cigar or the like with a liquid colloidal system distributed therethrough at least one coloring material adapted to color said wrapper and at least one ash-forming substance belonging to the group consisting of titanium dioxide, magnesium carbonate, calcium carbonate, talcum and kaolin; drying said wrapper treated with said colloidal system so as to cause adherence of said coloring material and said ash-forming substance to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution of cellulose ethyl ether adapted to form a film upon drying; and drying said wrapper treated with said film-forming substance, thereby forming a film on said wrapper substantially covering said coloring material and said ash-forming substance.

4. In a method of improving the color and burning characteristics of cigars and the like, the steps of treating the wrapper of a cigar or the like with a liquid colloidal system distributed therethrough at least one coloring material belonging to the group consisting of chlorophyll, yellow wood extract, buckthorn berries extract, logwood extract, hematein, litmus, safflower, luteolein, humic acid and synthetic food colors, said coloring material being adapted to color said wrapper, and at least one ash-forming substance which upon burning forms an ash of predetermined color; drying said wrapper treated with said colloidal system so as to cause adherence of said coloring material and said ash-forming substance to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution of cellulose ethyl ether adapted to form a film upon drying; and drying said wrapper treated with said film-forming substance, thereby forming a film on said wrapper substantially covering said coloring material and said ash-forming substance.

5. In a method of improving the color and burning

characteristics of cigars and the like, the steps of treating the wrapper of a cigar or the like with a colloidal solution the continuous phase of which consists of an aqueous solution of a lower alcohol and which has distributed therethrough at least one coloring material adapted to color said wrapper and at least one ash-forming substance which upon burning forms an ash of predetermined color; drying said wrapper treated with said colloidal system so as to cause adherence of said coloring material and said ash-forming substance to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution of cellulose ethyl ether adapted to form a film upon drying; and drying said wrapper treated with said film-forming substance, thereby forming a film on said wrapper substantially covering said coloring material and said ash-forming substance.

6. In a method of improving the color and burning characteristics of cigars and the like, the steps of treating the wrapper of a cigar or the like with a liquid colloidal system distributed therethrough at least one coloring material adapted to color said wrapper and at least one ash-forming substance which upon burning forms an ash of predetermined color; drying said wrapper treated with said colloidal system so as to cause adherence of said coloring material and said ash-forming substance to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution of cellulose ethyl ether adapted to form a film upon drying; and drying said wrapper treated with said film-forming substance thereby forming a film on said wrapper substantially covering said coloring material and said ash-forming substance.

7. In a method of improving the color and burning characteristics of cigars and the like, the steps of treating the wrapper of a cigar or the like with a liquid colloidal system distributed therethrough at least one coloring material adapted to color said wrapper and at least one ash-forming substance which upon burning forms an ash of predetermined color; drying said wrapper treated with said colloidal system so as to cause adherence of said coloring material and said ash-forming substance to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution in a solvent comprising water and at least one member of the group consisting of methanol, ethanol, propanol, isopropanol, butanol, butyl acetate, ethyl glycol, methyl glycol, acetone, methyl ethyl ketone, carbon tetrachloride, trichlorethylene, perchlorethylene, and chloroform, of cellulose ethyl ether adapted to form a film upon drying; and drying said wrapper treated with said film-forming substance thereby forming a film on said wrapper substantially covering said coloring material and said ash-forming substance.

8. In a method of improving the color and burning characteristics of cigars and the like, the steps of treating the wrapper of a cigar or the like with a colloidal solution, the continuous phase of which consists of an aqueous solution of a lower alcohol and which has distributed therethrough at least one substance belonging to the group consisting of gum arabic, tragacanth and starch, at least one coloring material belonging to the group consisting of chlorophyll, yellow wood extract, buckthorn berries extract, logwood extract, hematein, litmus, saf-

flower, luteolein, humic acid and synthetic food colors, said coloring material being adapted to color said wrapper, and at least one ash-forming substance belonging to the group consisting of titanium dioxide, magnesium carbonate, calcium carbonate, talcum and kaolin; drying said wrapper treated with said colloidal solution so as to cause adherence of said coloring material and said ash-forming substance to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution of cellulose ethyl ether adapted to form a film upon drying; and drying said wrapper treated with said film-forming substance, thereby forming a film on said wrapper substantially covering said coloring material and said ash-forming substance.

9. In a method of improving the color and burning characteristics of cigars and the like, the steps of treating the wrapper of a cigar or the like with a colloidal solution having a continuous phase consisting essentially of an aqueous solution of a lower alcohol and having a disperse phase consisting of at least one substance belonging to the group consisting of gum arabic, tragacanth and starch having distributed therethrough at least one coloring material belonging to the group consisting of chlorophyll, yellow wood extract, buckthorn berries extract, logwood extract, hematein, litmus, safflower, luteolein, humic acid and synthetic food colors, said coloring material being adapted to color said wrapper, and at least one ash-forming substance belonging to the group consisting of titanium dioxide, magnesium carbonate, calcium carbonate, water-soluble calcium, magnesium and aluminum salts, talcum and kaolin; drying said wrapper treated with said colloidal solution so as to cause adherence of said coloring material and said ash-forming substance to said wrapper, whereby said wrapper is given a desired color before the cigar or the like is smoked and whereby the ash of the cigar or the like upon smoking of the same is also given a desired color; treating said wrapper with said coloring material and said ash-forming substance thereon with a solution of cellulose ethyl ether in a solvent comprising water and at least one member of the group consisting of methanol, ethanol, propanol, isopropanol, butanol, butyl acetate, ethyl glycol, methyl glycol, acetone, methyl ethyl ketone, carbon tetrachloride, trichlorethylene, perchlorethylene and chloroform, said solution being adapted to form a film upon drying; and drying said wrapper treated with said film-forming substance thereby forming a film on said wrapper substantially covering said coloring material and said ash-forming substance.
